UNITED STATES PATENT OFFICE

JOHN T. QUIGLEY, OF LOS ANGELES, CALIFORNIA

LABEL-HOLDING REMOVABLE CLIP FOR FILE SHEETS

Application filed October 24, 1927. Serial No. 228,243.

This invention relates to a label holding detachable clip for file sheets and an object thereof is to provide a clip that can be easily and quickly attached to and detached from the edges of unperforated file sheets so that it is transferable from sheet to sheet when it is desirable or necessary to be so moved. In other words the clip is constructed so that it can be easily attached to any ordinary file sheet and when so attached is relatively fixed to the sheet until the sheet is to be replaced for any cause such as being worn or soiled, in which event the clip can be easily and quickly detached from the worn sheet by simply moving it in a direction parallel relative to the edge to which it is attached until displaced.

Another object of this invention is to provide a detachable label holding sheet metal clip that can be attached to the top edge portion of a file sheet without any previous preparation of the sheet; and which is adapted to be freely moved parallel with the top edge and from side to side of the sheet, and which at all times is adapted to resist movement in a direction that is endwise of the sheet to which it is attached and to resist such movement to the full tensile strength of the paper.

Another object of the invention is to provide a clip for filing tags, cards, sheets or folders that can be used indefinitely and which is easily made and which can be manufactured and sold cheaply.

Another object is to provide a clip for file sheets that is adapted to be attached to paper sheets in common use as file folders and guide cards, particularly folders and cards cut with upwardly projecting tabs integral with the sheet.

40 A feature of the invention is shown in the arrangement of the clip detents whereby they permit a relatively free movement of the clip along the paper from side to side thereof but positively prevent movement of the clip endwise of the sheet to which the clip is attached.

45 A feature of invention is shown in the laying out of the clip, whereby it, including properly arranged detents and apertures, can be stamped out of thin sheet metal in a one

piece body ready to be folded or bent into proper form, so that by means of stamping and bending machines the clips can be cheaply supplied to consumers at low cost and in large quantities as may be desired.

55 Other objects, advantages and features of invention may appear from the accompanying drawings, the subjoined detailed description and the appended claims.

50 The accompanying drawings illustrate the invention.

Figure 1 is a perspective view of a file folder for vertical filing with a clip attached thereto that is constructed in accordance with this invention. Fig. 2 is a grouped side and edge view of a sheet metal blank ready to be bent into proper form. Fig. 3 is a plan view of the clip after it has been bent into proper form. Fig. 4 is an underside view of the clip shown in Fig. 3. Fig. 5 is an enlarged cross section on line 5—5, Fig. 4, showing the detent slightly exaggerated in size for the purpose of illustration. Fig. 6 is a sectional view analogous to Fig. 5 showing the clip attached to an upper edge portion of a filing sheet 70 and with a label and transparent cover or shield properly arranged over the upper edge portion of the file sheet. Fig. 7 is an enlarged diagrammatic view of the clip showing the lower end and open sides so it can be easily attached to the sheet edge. Fig. 8 is an enlarged cross sectional view analogous to Fig. 5 showing the clip with a slightly exaggerated 75 detent at the apex of the angle between the vertical and inclined portion of the clip walls. Fig. 9 is a view analogous to Fig. 8 showing the clip attached to a file sheet with the upper edge portion covered by a label and transparent cover. Fig. 10 illustrates the

80 first step in preparing the upper edge portion of a file sheet for attaching the clip to a file sheet. Fig. 11 illustrates the second step in preparing the upper edge portion of the sheet for attaching it to the clip. Fig. 12 illustrates the upper edge portion of the file sheet after 85 the first and second steps are completed. Fig. 13 illustrates the final step in attaching the clip to a file sheet and its normal position thereon. Fig. 14 is a side view of an index

90 card or file sheet that is not provided with 95 100

the usual upwardly extending integral tab, showing the clip attached to an edge portion of the sheet.

As previously indicated the clips are first stamped out of sheet metal into blanks such as the blank 15 shown in Fig. 2, after which the blank is folded or bent into the form shown in Figs. 3 and 4.

As the blank is stamped out it is also perforated to form the detents 16 that function to assist in preventing the clips from being displaced from the filing sheet 17 in a direction endwise thereto; and simultaneously with forming these detents an aperture or window 18 is stamped in the blank through which the index names and data are visible when the clip is in use.

After the blanks are stamped out in the form shown in Fig. 2, they are then folded adjacent the dotted lines 19, 20 and 21 into the forms best shown in Figs. 3, 4, 5, 7 and 8; in which the front and rear walls are connected at their top and open at the sides and bottom and parallel throughout. These walls include the bottom portions 22 and 23 that in use normally occupy a vertical position and form front and rear supports for the top portions 24 and 25 that are inclined or arranged angularly to the bottom portions and are spaced apart so there is an angular space between the walls. The space between the portions 24, 25 form a chamber 26 therein adapted to receive a portion of the top edge 27 of the filing sheet 17 together with a label slip 28 and a transparent shield 29.

If desired the blank can be folded so as to form the chamber 26 with more or less space between the walls 24 and 25 so that labels or index cards of greater or less thickness can be used; and preferably the front and rear supports 22, 23 are spaced a distance apart slightly less than the thickness of the filing sheet to which the clip is attached so that they will pinchingly engage the sheet to prevent accidental movement of the clip sidewise thereon, there being sufficient tension in the metal for the foregoing purpose. This engagement of the vertical wall portion with the sheet is not sufficient to prevent the clip from being manually and freely moved endwise from side to side of the sheet.

The clip is folded so that the points of the detents 16 extend into the chamber 26 adjacent the apex of the angle between the walls so that in use the sheet 17 at its fold 30 extends over the points of the detents in a slightly tortuous bend, as best shown in Figs. 6 and 9, so that when the clip is lifted in a direction to suspend the sheet in a vertical position it will not be detached therefrom. This arrangement of parts, as previously stated, does not prevent the clip from being manually moved sidewise on the file sheet either to place it on or detach it from the sheet, there being

no perforations through the sheet to prevent such sidewise movement.

The clip is placed on the sheet as best shown in Figs. 10 to 13 inclusive. As shown in Figs. 10 and 11 the clip is first used as a tool to bend the upper edge portion 27 of the sheet 17 to a proper angle to be inserted into the chamber 26. That is the upper edge portion of the sheet 17 is first inserted between the vertical portions 22, 23, of the walls as indicated in Fig. 10. Then using the inner bottom edge of the portion 23 as a pivot the clip is turned in the arc $a-b$ until the top engages the file sheet, which operation forms an angle or crease 30 at the proper distance from the upper edge of the sheet to conform to the angular space between the walls of the clip, which angle is indicated in Fig. 12. The top angular portion of the sheet is then attached to the clip by extending the edge portion 27 into the chamber 26 and an adjacent portion of the sheet between the walls 22, 23 with the crease 30 riding over the points of the detents 16 as best shown in Figs. 6, 9 and 13. In other words after the fold or crease 30 is formed the clip can be easily attached by slipping it endwise over the sheet and keeping the angle of the clip in alignment with the angle of the paper. Then, if the sheet be held stationary gentle pressure on the clip will move it horizontally along the edge portion of the sheet 17, and the clip will slide easily over the detents by reason of their rounded corners. This angular arrangement of the vertical and inclined portions of the front and rear walls to which the sheet at this portion conforms, and the detents contacting with the sheet 17 on its fold 30, hold the clip from displacement endwise of the sheet. Then, with the clip so arranged, the label or index card 28 and its transparent shield or cover 29 can be inserted into the chamber 26 between the portion 27 of the sheet and the upper wall 24 so that the subject-matter on the index or record card is visible through the aperture 18. The chamber 26 has open ends so that the label and shield can be inserted from either end.

Normally the wall portions 22, 23 stand vertical in a file and the upper wall portions 24, 25 are preferably inclined about thirty degrees out of a vertical line so that the subject-matter on the label or index cards can be easily read. It is understood, however, that the inclination can be more or less as may be desired.

For use upon wide paper sheets not provided with integral tabs the relative proportions of the clip hereinbefore illustrated are changed by extending the width of the body portion of the clip containing the aperture or window to a position above the sheet as shown in Fig. 14.

It is understood that the clip may be made either with or without the detents as the ver-

tical wall portions are arranged to frictionally engage the sheet and the angle between them, and the position of the upper wall portion effects a hold on the sheet at the fold 30 that in ordinary use, prevents a displacement of the clip endwise of the sheet.

Also it is understood that the clips may be made in various sizes and lengths and may be provided with any desired number of detents for engaging the file sheet. Also they may be formed of any suitable material and in various ways without departing from the principles of the invention.

I claim as my invention:

1. A label holding clip for vertical file sheets, consisting of an upper label holding portion, a lower portion with a horizontally extending angle between said portions, and a detent extending into said angle in position to engage the file sheet and prevent vertical displacement of the clip therefrom but permit lateral movement of the clip on the file sheet.

2. A detachable index clip comprising two substantially parallel walls joined at their tops and separated at each end and at the bottom and bent to form an angle extending horizontally from end to end of each of said walls, the upper portion of each of said walls being extended backward at an inclination from the lower portion of said walls, and a detent extending into the angular space between said walls adjacent the apex of said angle.

3. A label holding clip for vertical file sheets, consisting of a folded upper label holding portion, a lower portion bent horizontally so that said upper portion will extend at an angle to said lower portion, and a detent extending upward into close proximity to the upper side of said upper portion, whereby said detent will engage the file sheet and prevent upward displacement of the clip, and the angular position of said upper portion of the clip will prevent the downward displacement of the clip on the file sheet.

4. A detachable label holding clip for vertical file sheets including upper and lower inclined parallel walls connected at their upper ends and having a chamber between them adapted to receive an upper edge portion of an unperforated file sheet, front and rear vertical parallel walls integral with the lower ends of the inclined walls, that are spaced apart a less distance than the thickness of a file sheet, a detent adjacent the apex of the angular space between the walls that is arranged to engage the under side of the sheet at its bend and prevent vertical displacement of said clip.

5. The combination set forth in claim 4, and a label detachably extended into the chamber between said upper and lower walls and over the edge portion of the file sheet, 65 a removable transparent shield arranged over

said label so that the edge portion of the file sheet is forced into frictional engagement with said lower wall and detents, and an elongated aperture in the top wall of said body through which said label is visible.

6.. A label holding clip for vertical file sheets including a sheet metal blank bent to form upper and lower inclined parallel walls having a chamber between them adapted to receive an edge portion of an unperforated file sheet, front and rear walls integral with said inclined walls, detents integral with the rear wall that extend into the chamber in position to engage the under side of the edge portion of the file sheet, a label extending through the chamber above said detents and over the file sheet, a transparent cover over said label, and an aperture through said upper wall through which said label is visible.

In witness whereof, I have hereunto affixed my signature.

JOHN T. QUIGLEY.
